DESIGN FOR A FISHHOOK

John K. Russell, North Hollywood, Calif.

Application May 20, 1948, Serial No. 146,496

Term of patent 14 years

(Cl. D31—4)

To all whom it may concern:

Be it known that I, John K. Russell, a citizen of the United States, residing at North Hollywood, in the county of Los Angeles and State of California, have invented a new, original, and ornamental Design for a Fish Hook, of which the following is a specification, reference being had to the accompanying drawing, forming part thereof, in which:

Fig. 1 is a perspective view of a fish hook embodying the present design;

Fig. 2 is a side elevational view;

Fig. 3 is a plan view; and

Fig. 4 is an end view of the same.

I claim:

The ornamental design for a fish hook, as shown.

JOHN K. RUSSELL.
